DESIGN FOR A HAT

Elizabeth Schoen, New York, N. Y.

Application December 28, 1938, Serial No. 82,024

Term of patent 7 years

To whom it may concern:

Be it known that I, Elizabeth Schoen, a citizen of the United States, residing at New York, in the county and State of New York, have invented a new, original, and ornamental Design for a Hat, of which the following is a specification, reference being had to the accompanying drawing, forming part thereof, wherein—

Fig. 2 is a rear perspective view, and
Fig. 3 is a bottom plan view of a hat showing my new design.

I claim:

The ornamental design for a hat, substantially as shown.

ELIZABETH SCHOEN.
